UNITED STATES PATENT OFFICE.

PETER HARDMAN, OF WILLIMANTIC, CONNECTICUT, ASSIGNOR TO AMERICAN THREAD COMPANY, OF JERSEY CITY, NEW JERSEY, A CORPORATION OF NEW JERSEY.

TWISTING-MACHINE.

No. 886,698.

Specification of Letters Patent.

Patented May 5, 1908.

Application filed October 9, 1905. Serial No. 281,900.

To all whom it may concern:

Be it known that I, PETER HARDMAN, a citizen of the United States, residing at Willimantic, county of Windham, Connecticut, have invented certain new and useful Improvements in Twisting-Machines, of which the following is a full, clear, and exact description.

My invention relates to improvements in machines for twisting thread, yarn, and the like.

The object of the invention is to construct a machine which will require a minimum amount of power to drive, which can be run at a high rate of speed, which will be simple to operate and will produce uniform results.

The invention consists in improvements, the principles of which are illustrated in the accompanying three sheets of drawings.

Briefly, the improvements consist in new and improved mechanism for controlling the feed of the strands to the flier and means for controlling the speed of rotation of the bobbin, which is rotated by the thread being wound.

The machine as actually constructed comprises a longitudinal shaft having tight and loose pulleys driven from a countershaft. From this longitudinal shaft two series of machine units are driven, twelve on each side. I have shown herein only the construction of two oppositely arranged units. Each unit comprises mechanism for the control of a single spindle.

Figure 1 is an end view of the machine showing the two oppositely arranged units, parts of the right hand unit being shown in section. Fig. 2 is a side view and partial section of one unit. Fig. 3 is a side view of the rolls and gearing for controlling the feed of strands to the flier. Fig. 4 is an end view of the same, one of the rolls being shown in dotted lines in a position released from the other roll. Fig. 5 is a detail of a catch secured to the arm of the outer roll. Fig. 6 is a sectional view of guide-rollers and a trough containing water for moistening the strands. Fig. 7 is an end view of the same, the guide-rollers being shown dotted in their raised position. Fig. 8 is a view of the bobbin and its carriage and control mechanism. Fig. 9 is a plan view of the control mechanism, the bobbin being shown in section. Fig. 10 is an end view of the same. Fig. 11 shows the flier and bobbin and the driving trains.

1 indicates the frame of the machine.

2 is the main longitudinal shaft having a suitable pulley 3 to be driven from a countershaft.

4 is a bevel gear on the main shaft 2.

5 is a bevel pinion on shaft 6 which will be termed the driving shaft.

The two mechanisms or units on the right and left hand of the section line X—X in Fig. 1 are the same, consequently only one will be described. The pinion 5 is in mesh with gear 4 and thus the twisting unit is driven.

7 is a clutch disk mounted on shaft 6 to rotate therewith, but longitudinally movable to a limited extent.

8 is a pulley located between collars fixed on shaft 6 but not otherwise connected thereto.

9 is a hand lever connected by arm 10, link 11 and lever 12 with the clutch 7 for throwing it into and out of engagement with the pulley 8, thus connecting or disconnecting the pulley from the driving shaft to start or stop the machine. Hand lever 9 and arm 10 are shown in full on the left hand unit and dotted on the right hand unit.

13 is the flier having a pulley 14 connected by a belt 15 to pulley 8.

16 is a hollow shaft of the flier acting as a twisting chamber for the strands 17, and having suitable bearings in the frame of the machine.

18 indicates the spools from which the strands are drawn to the flier. Any number of these may be employed according to the number of strands which the twisting thread is to have. They are located in a convenient place at the sides of the machine.

19 is a small cup or trough for containing water which is fed in through pipe 20 for moistening the strands.

21 and 22 are porcelain guide-rollers over and beneath which the strands are passed and which serve to hold the strands in the cup 19. The roller 22 is mounted to rotate on a stationary axis above the level of the water in the cup, but the roller 21 is mounted on an axis carried by the arm 23.

24 is a handle outside the cup which is connected to the arm 23 so that the roller 21 may be lifted out of the cup and the strands readily passed over the free end. The handle 24 is held in place frictionally so that the ordinary pull of the strands does not dis-

turb the position of the roller 21 in the cup. As the cup is of small size, only a small quantity of water is exposed at a time. This prevents the accumulation of dirt and 5 consequent soiling of the product.

25 and 26 are two rollers for controlling the feed of the strands to the flier. These are driven at a positive rate of speed relative to the flier.

10 27 is a worm on the flier shaft 16, driving the worm gear 28 which is on the shaft with the sprocket 29.

30 is a chain connecting sprockets 29 and 31.

15 33 is a gear rast on the shaft of the sprocket 31 in mesh with gear 34 which is on the shaft of the roller 25 and gear 35.

36 is a gear in mesh with gear 35 and on the shaft of the roller 26.

20 37—37 are arms pivoted on rod 38 and carrying the shaft of the roller 26 and gear 36.

When the parts are in the normal position, the strands of thread are gripped between the rollers 25 and 26, and the rollers are driven positively from the flier shaft. When it is desired to stop the feed of strands the roller 26 may be disengaged from the roller 25, the gear 36 at the same time being thrown out of mesh with the gear 35 by simply tilting the frame 37—37 away from the roller 25, as shown in dotted lines in Fig. 4. At this time the dog 39 carried by the frame 37 and having an L-shaped slot 40, catches on the roller shaft 41, holding the frame with the roller 26 disengaged from the roller 25. The shaft of the sprocket 31 and gear 33 being removably clamped to the frame in slot 32, it is very easy to remove the gear 33 and replace it with another having more or less teeth depending upon the rate of feed control desired.

42 is the bobbin or spool upon which the twisted thread is wound.

43—43 are stationary rods on which the 45 bobbin carriage 44 is guided.

45 is a dead or stationary spindle mounted rigidly on the bobbin carriage.

46 is a sleeve rotatably mounted on the spindle 45 and prevented from longitudinal 50 removal by the cap 46', which is attached to the spindle.

47 is a flange preferably integral with the sleeve 46 and having means of engagement or connection with the bobbin 42. The bobbin and the sleeve 46 are rotated by the pull of the thread which is being wound. As the thread is being wound, the bobbin is reciprocated longitudinally relative to the flier by the system of gears consisting of sprocket 48, 60 chain 49, sprocket 50, worm 51, worm wheel 52, shaft 53 and cam 54.

55 55 is a vertically movable pin projecting from the lever 55' pivoted to the bobbin frame into a groove in the cam 54.

65 56 is a hand lever pivotally mounted in the

bobbin carriage and having one arm connected to the lever 55'.

57 is a spring normally holding lever 55' with the pin in the groove of the cam. The bobbin carriage may be disengaged from the reciprocating cam 54 by operating the lever 56.

The flier is driven at a high rate of speed, for instance 1500 revolutions per minute. If the thread is desired to have say five twists or turns per inch of length, the thread must be fed through the flier shaft at the rate of one-fifth of 1500, or 300 inches per minute.

The customary bobbin is six inches in circumference when empty, so that the bobbin must rotate relative to the flier at the beginning of the operation at the rate of one-sixth of 300, or 50 revolutions per minute, which is an actual angular speed of 1500 minus 50, or 1450.

When the bobbin has increased in size to a circumference of say ten inches, it is obvious that with the same rate of feed of strands the bobbin must make fewer revolutions relative to the flier, namely, one-tenth of 300, or 30, or an actual angular speed of 1470 revolutions per minute. In other words, its actual speed has increased 20 revolutions per minute.

This actually takes place by reason of the increased diameter of the bobbin and its consequent leverage as the bobbin builds up, without materially varying the tension on the thread.

80 The necessary retardation of the bobbin is afforded by the mechanism shown on Sheet 3 of the drawings. 60 and 61 are two drums of different diameters carried by the sleeve

46, and preferably of steel, having their faces grooved. 62 and 63 are drums correspondingly shaped, formed preferably of some material such as papier-mâché, and mounted on the shaft 64 carried by the arm 65 which is pivoted on rod 66.

67 is a screw-threaded post pivotally mounted in the bobbin carriage and projecting through an opening in the arm 65, and having an adjusting nut 68 whereby the pressure of the drums 62 and 63

100 against the drums 60 and 61 may be increased or diminished as desired. The two drums 60 and 61 of course rotate with the bobbin and at an increasing speed as the bobbin is being wound. The ratio of the diameters of the drums 60—61—62—63 is such

105 that a slippage occurs between the two pairs of drums which affords the frictional resistance necessary to cause the bobbin to lag behind the flier. The heat produced by the

110 friction is quickly dissipated, since the surfaces of the drum are constantly moving. The friction remains practically constant during the operation of the machine and consequently the resistance to rotation of the

115 bobbin is substantially constant. Hence the tension in the thread remains constant and the product of the machine is of uniform

120 twist, density and diameter. The arm 65, together with the drums 62 and 63 may be

125 130

130

130

130

130

130

130

readily removed when the nut 68 is taken from the post 67 for the purpose of repairing or replacing the drums when necessary.

The advantages of the construction will be apparent to those who are skilled in the art.

What I claim is:

1. In a twisting machine, the combination of a bobbin, a flier, means for driving said flier, a hollow flier shaft, a pair of rollers 10 geared to each other having driving connections with the flier shaft for controlling the feed of strands through said shaft to said flier, and a movable frame supporting one of said rollers whereby said roller may be disengaged from the other roller.

2. In a twisting machine, the combination of a bobbin, a flier, means for driving said flier, a hollow flier shaft, a pair of rollers 20 geared to each other and having driving connections with said flier shaft for controlling the feed of strands through said shaft to said flier, a movable frame supporting one of said rollers whereby said roller may be disengaged from the other roller and supported in its 25 disengaged position.

3. In a twisting machine, a flier, means for driving said flier, a spindle, a sleeve rotatably mounted thereon and adapted to carry the bobbin, two drums rotatable with said sleeve 30 and two rotatable drums connected together and engaging said sleeve drums, the ratio of the diameters of the contacting pairs of drums being different.

4. In a twisting machine, a flier, means for 35 driving said flier, a spindle, a sleeve rotatably mounted thereon and adapted to carry the bobbin, two drums rotatable with said sleeve, two rotatable drums connected together and engaging said sleeve drums, the ratio of the 40 diameters of the contacting pairs of drums being different, and means for adjusting the pressure of one pair of drums against the other.

5. In a twisting machine, a flier, means for 45 rotating said flier, a bobbin carrying sleeve adapted to be driven by the thread being wound, means for controlling the rate of feed of strands to said flier and bobbin, a pair of drums rotatable with said sleeve, and a second pair of drums of different diameters frictionally engaging said sleeve drums for the 50 purpose specified.

6. In a twisting machine, a flier, means for 55 rotating said flier, a bobbin carrying sleeve adapted to be driven by the thread being wound, means for controlling the rate of feed of strands to said flier and bobbin, a pair of grooved drums rotatable with said sleeve, and a second pair of grooved drums of different diameters frictionally engaging said sleeve 60 drums the ratio of the diameters of the contacting pairs of drums being different for the purpose specified.

7. In a twisting machine, a flier, means for 65 driving said flier, a bobbin carrying sleeve adapted to be driven by the pull of the thread

being wound, a pair of metal drums rotatable with said sleeve, and a pair of softer drums of material such as papier-mâché frictionally engaging said metal drums the ratio of the diameters of the contacting pairs of drums 70 being different.

8. In a twisting machine, a flier, means for driving said flier, a bobbin carrying sleeve adapted to be driven by the pull of the thread being wound, a pair of grooved metal drums 75 rotatable with said sleeve, and a pair of softer grooved drums of material such as papier-mâché frictionally engaging said metal drums the ratio of the diameters of the contacting pairs of drums being different. 80

9. In a twisting machine, a flier, means for driving said flier, a bobbin carrying sleeve adapted to be driven by the pull of the thread being wound, a pair of metal drums rotatable with said sleeve, a pair of softer drums of material 85 such as papier-mâché frictionally engaging said metal drums, the ratio of the diameters of the contacting pairs of drums being different and means for adjusting the pressure between said drums. 90

10. In a twisting machine, a flier, means for driving said flier, a bobbin carrying sleeve adapted to be driven by the pull of the thread being wound, a pair of grooved metal drums rotatable with said sleeve, a pair of softer 95 grooved drums of material such as papier-mâché frictionally engaging said grooved metal drums, the ratio of the diameters of the contacting pairs of drums being different and means for adjusting the pressure 100 between said metal drums.

11. In a twisting machine, a flier, means for rotating said flier, a bobbin carrying sleeve, drums rotatable therewith, a second pair of drums engaging said first mentioned pair of 105 drums, the ratio of the diameters of the contacting pairs of drums being different, a pivoted arm carrying said second mentioned pair of drums, a pivot pin supporting said arm, means for holding said arm with said 110 drums in engagement, said arm being removable from said pin when said drums are disengaged.

12. In a twisting machine, a flier, means for 115 rotating said flier, a bobbin carrying sleeve, grooved drums rotatable therewith, a second pair of grooved drums engaging said first mentioned pair of grooved drums, the ratios of the diameters of the contacting pairs of drums being different, a pivoted arm carrying said second mentioned pair of grooved drums, a pivot pin supporting said arm, means for holding said arm with said grooved drums in engagement, said arm being removable from 120 said pin when said grooved drums are disengaged. 125

PETER HARDMAN.
